10 Claims. (Cl. 18—11)

This invention relates to a method and means for obtaining coils from lengthy stock material.

Up to the present, when coiling thermoplastic wire and strip material, such material was helically wound on a rotating mandrel until the desired length of the coil had been attained, whereupon the coil, together with the mandrel carrying the same, was introduced into a hot and subsequently into a cold water bath, and the mandrel then was removed from the coil for the use of manufacturing another coil. Such known procedure obviously is rather time-consuming and complicated, in particular on account of the requirement of several water baths.

The main object of my present invention is to provide means eliminating said disadvantage. The present invention essentially proposes to heat thermoplastic stock material by a stream of gas while said material is being fed to coiling tools, whereupon the turns produced are cooled by a stream of a gaseous medium.

The thermoplastic stock material is conveyed according to the new process through a hot air stream and, immediately thereafter, the coil is cooled by means of an air stream.

The invention further deals with means for carrying into effect the aforesaid process, said means comprising rollers for feeding the stock, coiling tools which control the diameter of the coil to be produced and the pitch of the helical turns, and two nozzles disposed immediately adjacent said tools, one of said nozzles communicating with means for producing a heating stream of a gaseous medium, and the other of said nozzles communicating with means for producing a cooling stream of a gaseous medium.

The apparatus advantageously may be so constructed that it may be used either for the production of coils of thermoplastic stock or metallic stock, whereby in the latter case the gas streams are cut out.

One embodiment of my present invention is shown in the accompanying drawings, in which:

Fig. 1 shows the upper portion of a coiling machine in elevation and partly in vertical section taken on line I—I of Figs. 3 and 5,

Fig. 2 is a side view of the machine, partly in vertical section taken on line II—II of Fig. 1,

Fig. 3 is a cross-section taken on line III—III of Fig. 1,

Fig. 4 is a vertical section taken on line IV—IV of Fig. 3, and

Fig. 5 shows a detail of the machine, partly in side view and partly in a vertical section taken on line V—V of Fig. 1, and drawn to an enlarged scale.

The coiling machine shown comprises a box-like housing 10 in the lower part of which is disposed a reel 11 for the stock material, which is rotatably mounted on a vertical axle 12 (Fig. 2). Above the reel 11 is situated an electric drive motor 13 which is suspended from a carriage 14 which by means of sockets 15 is movably guided on two horizontal bars 16 which in turn are rigidly secured to the housing by means of lugs 17. Part-

2

allel to the bars 16 and intermediate thereof is arranged a threaded spindle 18 which is rotatably but axially immovably mounted and accommodated in the housing 10. The spindle 18 at one end carries a handwheel 19 which is disposed outside of the housing and through its threaded portion engages a nut 20 mounted on the carriage 14. By turning the handwheel 19, the carriage 14 and the motor 13 thus may be moved to and fro.

The motor 13 is provided with a V-belt pulley 21 (only schematically shown in the drawing), which comprises two conical half portions which, in known manner, are pushed against each other by a spring so as to maintain the V-belt 22 tightly in position. The belt 22 runs over a pulley 23 mounted on a drive shaft 24 which is rotatably mounted in the housing 10. A pinion 25 keyed to shaft 24 meshes with a gearwheel 26 which, as shown in Fig. 3, by means of a sleeve 27 is loosely mounted rotatable on a further shaft 28 which by means of ball-bearings 29 is rotatably mounted in the machine housing 10. A rotary body 30 is keyed to shaft 28 in an axially movable relation. A helical compression spring 31 tends to move the body 30 towards the gearwheel 26. The latter comprises a rim 32 which extends somewhat over body 30. The inner face of rim 32 is conical to thus coat with a conical lining 33 of body 30. Lining 33 consists of a material which increases the friction, such as rubber, fiber and the like. The gearwheel endface remote from body 30 abuts against a gearwheel 34 which is keyed to shaft 28, whereby the gearwheel 26 is secured against axial movement. Elements serving to move rotary body 30 are described further below.

Vertically above said shaft 28, a further shaft 35 is rotatably mounted in housing 10 by means of pendulum ball bearings 36. As shown in Fig. 2, a gearwheel 37 is mounted on said shaft 35, which coacts with gearwheel 34 and has the same number of teeth as the latter. The end of shaft 35 which faces the machine frontside is mounted by means of respective pendulum ball bearings 36 in a slide 38 which is vertically movable in a track or slot of housing 10. The slide 38 is guided by rails 39 which are secured to the housing by means of screws, as shown in Fig. 1. In the upper portion of slide 38 is provided a recess 40 in which is inserted a helical compression spring 41 of which the upper end bears against a plate 42. The latter is engaged to a set screw 43 which is screwed into block 45 secured to the housing-cover 44. Spring 41 thus tends to move the slide 38 downwardly.

The two shafts 28 and 35 on the machine frontside project from the housing 10, and each carries a transport roller 46. These two rollers are alike and destined to coat with each other. Each of these rollers is provided with circumferential grooves which are of substantially semicircular cross-section having different sizes. The rollers 46 are keyed to their respective shafts 35, 28, but are axially movable. For such purpose, the shaft-end is provided with a threaded portion, as shown in Fig. 2, on which is screwed a set nut 47. To the end-face of roller 46 is screwed a ring 48 which is engaged in a circumferential groove of nut 47 and thus interconnects the two elements 46 and 47 for axial movement. For the purpose of axially adjusting the rollers 46, therefore, only the nuts 47 have to be turned. The adjusted position of the rollers 46 is secured by means of a screw 49 which is screwed in the shaft-end and comprises a head projecting over the threaded portion of the shaft, which head may be tightened against nut 47 to locate the same.

To the machine frontside is pivoted a segment 50 on a pin 51. A clamping screw 52 passes through a slot in segment 50, which is curved concentrically with the pivotal axis of the segment and is threaded into the front-wall of housing 10. Screw 52 together with said slot,

limits the degree of swing of segment 50 and permits the latter to be located in adjusted position. In a recess of segment 50 a roller mount 53 is disposed for longitudinal movement by means of a threaded spindle 54 having a knob 55. A further clamping screw 56 serves for clamping the mount 53 in its adjusted position. The free end of mount 53 is provided with a rotatably mounted roller 57 which has a circumferential groove and, in the manufacture of the coil, serves as a coiling tool for bending the stock. A second roller 58, which serves the same purpose, is rotatably mounted on the free end of a second roller mount 59 which, by means of a spindle having a knob 60, is longitudinally movable in a recess of a block 61. To clamp the roller arm 59 in the adjusted position, a clamping screw 62 is provided. The block 61 by means of an axle 63 is movably mounted on segment 50 so that it may be swung out of the plane of swing of the latter. Such movement may be produced by means of a set screw 64 which is threaded in block 61 and of which the free end bears against an extension of segment 50 (not shown in the drawings). To positively locate the block 61 in its adjusted position, a further clamping screw 65 is provided. Said two rollers 57, 58 serve as pushers for forming the coil turns and, above all, determine the diameter of the latter. By swinging the block 61 out of the plane of segment 50, the pitch of the coil turns may be controlled to a certain degree. For the same purpose there is provided a finger 66 which laterally abuts against the resulting turns and which is disposed adjustably at one end of a pin 68 and may be positively located with the aid of a screw 67. Pin 68 is longitudinally movable and rotatable in a recess of segment 50, and may be positively located in desired position by means of a clamping screw 69.

In the range of the coiling tools 57, 58 and 66 is disposed a pin 70 (Figs. 1 and 5) which projects from the frontwall of the machine housing 10 at right angles thereto. Pin 70 is secured in a carriage 71 which is vertically guided in a slot 72. A set screw 73 serves to clamp the carriage 71 in its required position. As more clearly shown in Fig. 5, pin 70 comprises two concentrically nested tubes 74 and 75 of which the outer tube 74, is secured in carriage 71 by means of a bushing 76. The front end of tube 74 is closed with the exception of an aperture for the inner tube 75. A cap 77 is mounted on the front end of pin 70 and has a cross-bore 78 which communicates with the bore of inner tube 75 and opens in a longitudinal recess or slot 79 of cap 77. The cap together with the respective recesses 78 and 79 forms a nozzle. At some distance from cap 77, a ring 80 is mounted on the outer tube 74. A bore 81 passing radially through ring 80 and the wall of tube 74, opens into the longitudinal space existing between the two spaced tubes 74, 75. Ring 80 together with the respective bore 81 forms a second nozzle. The rear end of tube 75 communicates with a threaded nipple 82 which at one end is screwed into the bushing 76 and, at the other end, by means of a nut 83 is connected to a pipe conduit 84. A further threaded nipple 85 also is screwed into bushing 76 and, via a bore 86, communicates with the inside of tube 74. A pipe conduit 88 is connected to nipple 85 with the aid of a nut 87. At a suitable point in the machine housing 10 is disposed a compressor (not shown) and a motor for driving the same. The suction-side of the compressor is connected to pipe 84, and the pressure side is connected to pipe 88. The latter extends through an electric heating device (not shown). Air from the atmosphere is sucked through the nozzle 77-79 and ejected in heated state through the nozzle 80, 81.

A sleeve 89 is inserted in the front wall of the machine housing 10, as shown in Fig. 3. On the front portion of sleeve 89 is mounted a bushing 90 to which is secured, by screws, a frame 91, 92. The latter comprises a vertical plate 92 standing at right angles to the machine front

side and being provided with an eyelet 93 which is disposed below pin 70 and serves for guiding the stock to be coiled. Plate 92 is exchangeable in accordance with the stock diameter, and it also may be called a coiling tool. 5 Frame 91, 92 forms a guide for a vertically movable carriage 94 which comprises an arm carrying a roller 95 (Figs. 1 and 3). The latter is supported on an eccentric portion 96 of a shaft 97 which is rotatably mounted in said sleeve 89. By turning the shaft 97, carriage 94 thus may be moved upwardly or downwardly, the carriage weight being instrumental to hold the roller 95 in contact with the eccentric 96. A cutting tool 98 is secured to carriage 94 by means of a set screw 99. Tool 98 partly rests on plate 92, and, together with the latter, forms a 10 pair of scissors for severing the coils formed. Tool 98 may be adjusted relative to carriage 94 by means of a set screw 100, by loosening screw 99. Bushing 90 is 15 axially movable to permit adjustment of the eyelet 93 with respect to the two nozzles 77-79 and 80, 81 in the direction of pin 70. To facilitate such latter movement, a set screw 101 is disposed in the closed end-face of sleeve 90, of which the free end may bear against the shaft 97 or the eccentric lug 96 thereof. To clamp sleeve 90 in its position, a clamping screw 102 is provided. By 20 moving pin 70 with the aid of carriage 71, the spacing of the nozzles from eyelet 93 may be varied. On the driving shaft 24 is mounted a sprocket 103 which through a chain 104 is coupled to a second sprocket 105 (Figs. 3 and 4). Sprocket 105 is mounted on the driving axle of a steplessly variable gearing unit 106 which by means of a frame 107 is secured in the machine housing 10. To 25 permit adjustment of the gear 106, the latter is provided with a lever 108 which projects through the housing 10 therewithout. The axle of gear 106 carries a cam disk 109 which peripherally is engaged by a feeler roller 110 (Fig. 4). The latter is rotatably mounted on the free end of an arm 111 which is keyed on the inner end of said shaft 97. A cam 112 disposed on the circumference of disk 109 causes arm 111 to swing and, thereby, move the tool 98 upwardly. A spring (not shown) holds roller 110 in contact with the circumference of cam disk 109.

To one sidewall of housing 10 is pivoted, at 114, a two-arm lever 113 to move in a vertical plane. One arm of lever 113 carries a rotatable roller 115 through which it laterally contacts the disk 109. The latter is provided with a laterally projecting cam 116 which is capable of moving the lever 113. The other arm of the latter coacts with one arm of a further two-arm lever 117 which is pivoted on a pin 118 to housing 10 to move in a horizontal plane. The other arm of lever 117 carries an adjustable stop screw 119 which, as shown in Figs. 2 and 4, coacts with a web 120 which interconnects two parallel swing arms 121. On shaft 35 is mounted a sleeve 122 which is rotatable with respect to shaft 35 and is secured in its axial position by means of two rings 123. The two swing arms 121 are pivoted on pins 124 to said sleeve 122. Approximately at the midpoint of each arm 121 is secured a pin 125 which is engaged in a circumferential groove of said rotary body 30. The parts last described serve for axially moving the body 30 and, thus, for coupling the gearwheel 26 to the shaft 35, or, respectively, to disengage the gearwheel 26 from said shaft.

To manufacture coils of thermoplastic wire stock with the aid of the machine described, the procedure e. g. 65 may be as follows:

Two devices 126 and 127 secured to the frontwall of machine housing 10 serve for straightening the stock. Each of said two devices comprises the rotatable rollers 70, 75 between which the material must pass.

The wire stock is drawn off from the reel 11 and fed, through the two straightening devices 126 and 127, to the transport rollers 46. The latter clamp the wire under the action of spring 41 in one of their circumferential grooves. 75 The rollers 46 move the wire towards the coiling tools,

the wire running over the bore 81 of nozzle 80, 81. From the latter issues a hot-air stream through which the wire moves. The temperature of said airstream may be 80° C. for example, which is sufficient in order to make the stock plastically deformable. The wire thus softened is pushed towards the roller 57 where it is bent downwardly and then runs up on to the second roller 58. The latter performs the corresponding turn and, at the same time, imparts thereto a certain pitch. The wire then moves through the eyelet 93. The turn being formed then passes the finger 66 which corrects the pitch of the turns as required. The completed turns thereby are moved into the range of nozzle 77-79 through which cold air is sucked in from the atmosphere. The cold-air stream thus produced cools the turns so that the latter solidify in their new form. The pin 70 which is provided with the two nozzles, stands at right angles to the feeding direction of the rollers 46 and projects into the produced coil.

When the coil has attained the desired length, the cam 116 of disk 109 contacts the roller 115 whereby the arms 121 by means of the two levers 113, 117 are so actuated that they move the body 39 against the action of spring 31. The lining 33 thereby is disengaged from the rim 33 of gearwheel 26 which thus is uncoupled from shaft 35. The two rollers 46 thus stand still, and the wire feed is interrupted. In the next following moment, the cam 112 will be engaged by roller 110, and the arm 111 thereby is moved. Tool 98 thereby is moved upwardly so as to shear the wire running through eyelet 93. The coil produced thereby is severed.

Tool 98 then moves downwardly again, after cam 112 had passed the roller 110, and the gearwheel 26 under the influence of spring 31 is again coupled to shaft 35 when cam 116 leaves roller 115. The production of the coils then proceeds as described.

The length of the coils produced in relation to the length of wire stock required therefor, is determined by the gear ratio of gear unit 106 and may be adjusted by means of lever 108. The speed of production per se may be varied by means of handwheel 19, in that hereby the gear ratio between pulley 21 of the motor and pulley 23 of drive shaft 24 may be varied.

When the machine has to be set for working wire stock of another diameter, the rollers 46 by means of the adjusting nuts 47 may be axially moved so that those circumferential grooves which best fit the wire cross-section, will be situated in the track of the wires.

The machine described has the advantage that it permits the continuous production of coils of any desired length and that the cumbersome working with water is eliminated. The airstream used for cooling the turns is heated by the latter and already possesses a temperature higher than that of the atmosphere when being fed to the electric heating device (not shown), where it will be heated to approximately 80° C. and then blown towards the stock. In this manner, it is possible to use a comparatively weak heating device.

The machine, in slightly modified form, also may be used for working lengthy strip stock into coils. When the compressor and the electric heating device are eliminated, the machine described may also be used for making coils from metallic stock.

In a modification (not shown) the machine may comprise two coiling tools only one controlling the diameter of the coils to be produced, and the other controlling the pitch of the turns. Thus for example, one roller 57 and the finger 66 would suffice for bringing about the coiling operation.

What I claim as new and desire to secure by Letters Patent, is:

1. An apparatus for producing coils from lengthy thermoplastic stock material, comprising a plurality of coiling tools engageable with said stock material and arranged for controlling the diameter of the coils to be

produced and the pitch of the turns of said coils, a plurality of transport rollers for feeding said stock material to said coiling tools, a plurality of nozzle means disposed immediately adjacent said coiling tools and the path of movement of said stock material, first means for producing a heated stream of a gaseous medium and communicating with one of said nozzle means to blow said heated gaseous medium about said stock material immediately prior to the arrival thereof at said coiling tools, second means communicating with another of said nozzle means for drawing a cool stream of said gaseous medium about said coils immediately after formation thereof by said coiling tools, said first means and said second means communicating with one another, whereby said cool stream of said gaseous medium, after being heated by the cooling of said coils, is conducted from said second means to said first means for further heating and reuse as said heated stream of said gaseous medium.

2. Apparatus according to claim 1, further comprising a hollow member disposed substantially axially of said coils being formed by said coiling tools and projecting through at least a portion of said formed coils, said nozzle means being mounted on said hollow member, said hollow member defining in its interior a plurality of passageways, one of said passageways being in communication with said one of said nozzle means and with said first means, and another of said passageways being in communication with the other nozzle means and with said second means.

20 3. Apparatus according to claim 2, said hollow member comprising two concentrically arranged tubes having bores, the bore of the inner tube constituting said other passageway, and the space defined by the bore of the outer tube and provided between said inner tube and said outer tube constituting said one passageway.

25 4. The apparatus according to claim 2, further including means defining an eyelet for guiding the stock material with respect to said nozzle means, through which eyelet the stock material may pass.

30 5. The apparatus according to claim 4, said eyelet being adjustable in a direction substantially parallel to the axial direction of said coils formed by said coiling tools.

35 6. The apparatus according to claim 4, further including means for varying the spacing of said hollow member from said eyelet.

30 7. A method of producing coils from thermoplastic material, comprising the steps of passing said material through a first stream of hot gaseous medium to cause said material to become soft and pliable, transforming said material into coils while in such soft and pliable condition, passing said coils through a second stream of a relatively cool gaseous medium to cool said coils and fix the shape thereof, further heating said second stream, and subsequently reusing said heated second stream as said hot first stream, whereby the amount of heat required to raise the temperature of said second stream to the temperature at which said first stream is passed over said material is reduced by virtue of the heat originally absorbed by said second stream during cooling of said coils.

40 8. In an apparatus for producing coils from thermoplastic material; transport roller means for feeding said material, at least one forming roll positioned in the path of feeding movement of said material, said material contacting the periphery of said forming roll and being fed past the same to be bent thereby into coil shape, a hollow, stationary pin extending substantially at right angles to the direction of feeding movement of said material and substantially axially of the turns of coils formed by said forming roll, said pin extending into the interior of said coils adjacent said forming roll and being spaced from said coils, said pin being provided in its interior with two passageways, a first nozzle carried by said pin communicating with one of said passageways and located adjacent the path along which said material is led, a

second nozzle carried by said pin adjacent said first nozzle and communicating with the other of said passageways and located in said interior of said coils, a compressor having a pressure side and a suction side, a first conduit connecting the pressure side of said compressor to said one passageway and to said first nozzle, a second conduit connecting the suction side of said compressor to said other passageway and to said second nozzle, and heating means located in at least one of said conduits for additionally heating a gaseous medium drawn in through said second nozzle and subsequently to be expelled through said first nozzle to soften said material prior to contact thereof with said forming roll.

9. In an apparatus according to claim 8, guide means located adjacent said forming roll and provided with an eyelet through which said material passes immediately subsequent to its deflection by said forming roll, and means operatively connected to said guide means for adjusting the latter in a first direction parallel to the longitudinal axis of said pin and in a second direction perpendicular to said axis, whereby the spacing of the turns of said coils and the diameter of said turns may be varied.

10. The process of producing a coil-shaped article from stock material; comprising the steps of feeding said material to forming means, directing a stream of hot gaseous medium to said material to thereby ensure pliability of said material, transforming said material while pliable to coil formation by said forming means, thereafter directing a stream of a cooling gaseous medium to the coils thus obtained, removing said latter medium in counter direction to said hot gaseous medium, and further heating said cooling gaseous medium, after the latter is heated by said coils, for reuse as said hot gaseous medium.
